UNITED STATES PATENT OFFICE.

CLARA ELIZABETH ENSFIELD, OF FENNVILLE, MICHIGAN.

CROCHET-NEEDLE.

1,358,067.

Specification of Letters Patent.

Patented Nov. 9, 1920.

Application filed November 7, 1919. Serial No. 336,357.

To whom it may concern:

Be it known that I, CLARA ELIZABETH ENSFIELD, a citizen of the United States, and a resident of Fennville, in the county 5 of Allegan and State of Michigan, have invented certain new and useful Improvements in Crochet-Needles, of which the following is a specification.

My invention is an improvement in cro- 10 chet needles, and has for its object to pro- vide a needle wherein resilient holders are provided in connection with the handle, for engaging the ball and the thread, to prevent unwinding of the ball and to prevent ravel- 15 ling of the work, and to hold the ball, holder and the needle together.

In the drawings:

Figure 1 is a perspective view of the improved needle;

Fig. 2 is a top plan view;

Fig. 3 is a side view.

In the present embodiment of the invention, the needle 1, which is of ordinary construction having at one end the hook 2 25 and having the other end plain, as shown at 3, is provided intermediate its ends with a flattened portion, in the present instance a loop, as shown, for convenience in grasping the needle.

Upon one side of the needle there is se- 30 cured a spring plate 5, the said plate having one end soldered, brazed or otherwise connected to the handle of the needle. Toward its free end the plate is bent outwardly away 35 from the needle and then inwardly to lie against the handle, as shown at 6, the ex- tremity of the said free end being also curved outwardly.

This plate 5—6 is designed to engage the thread on the ball to hold the ball to the 40 needle and to prevent unwinding of the thread upon the ball. On the opposite side there is secured a spring plate 7, the said plate being brazed, soldered or otherwise secured to the handle at one end and the 45 other end is bent outwardly, as shown at 8.

The outward bends of the plates 5 and 7 at their free ends are for the purpose of facilitating the entrance of the thread beneath the plates. The plate 7 is for holding 50 the thread near the work, to prevent raveling. Since a considerable amount of thread is to be grasped by the plate 5 it is bent outwardly intermediate its ends, and since but a single thread passes beneath the plate 55 7 it is not bent outwardly to receive said thread.

With the improved needle both work and ball are held to the needle so that all of the elements required for crocheting are together, and there is no chance of the ball 60 rolling away to unwind the thread.

The plate 7 also acts as a tensioning device for thread during crocheting. The plates for holding the ball and thread are in 65 use, however, as a rule, only when the work is laid aside.

I claim:

A crochet needle having at the end remote from the hook, a pair of spring plates 70 secured to opposite sides of the needle, and adapted to clasp the thread between them and the needle, said plates being connected at the ends of the plates remote from the hook of the needle.

CLARA ELIZABETH ENSFIELD.
